ARTHUR O. AUSTIN, OF NEAR BARBERTON, OHIO, ASSIGNOR, BY MESNE ASSIGNMENTS,
TO THE OHIO BRASS COMPANY, OF MANSFIELD, OHIO, A CORPORATION OF NEW
JERSEY

CURRENT TRANSFORMER

Application filed October 17, 1929. Serial No. 400,267.

This invention relates to an improved type of current transformers, particularly applicable to high voltage lines, and has for one of its objects the provision of a current transformer adapted for a large range of current values.

Another object is to provide a current transformer which will automatically adjust itself to variations in the amount of current flowing.

A further object is to provide a current transformer in which the number of turns in the primary and secondary circuits may be simultaneously adjusted.

15 A further object is to provide a device of the class named which shall be of improved construction and operation.

Other objects and advantages will appear from the following description.

20 The invention is exemplified in the combination and arrangement of parts shown in the accompanying drawings and described in the following specification, and it is more particularly pointed out in the appended 25 claims.

In the drawings:

Fig. 1 is a fragmentary, vertical, sectional view showing a portion of a current transformer having one embodiment of the present invention applied thereto.

25 Fig. 2 is a fragmentary, vertical, sectional view with parts in elevation showing the top portion and reservoir of the bushing illustrated in Fig. 1.

Fig. 3 is a horizontal section substantially on line 3—3 of Fig. 2.

Fig. 4 is a fragmentary elevation substantially on line 4—4 of Fig. 2.

Fig. 5 is an elevation on line 5—5 of Fig. 4.

40 Fig. 6 is a section on line 6—6 of Fig. 2.

Fig. 7 is a wiring diagram of the transformer connections.

Fig. 8 is a wiring diagram showing a slightly different arrangement of connections for the primary windings.

Fig. 9 is similar to Fig. 8 but with the switches in a different position.

45 In high voltage transmission lines or other conductors operating at high voltages, it is frequently necessary and advisable to have

an accurate indication of the current flowing in the conductor. One common method used for obtaining an indication of the current, for the operation of relays, meters, tripping circuits or for other purposes, has been to use 55 a current transformer. Where the voltages are low, efficient current transformers are readily made, giving practically any ratio and phase angle with a high degree of accuracy. For high voltages, however, the ordinary forms of current transformers are 60 not well adapted, due to the fact that the large amount of insulation required between the conductor and the secondary and core or low voltage winding of the current transformer, requires considerable separation 65 space. This separation necessitates a long magnetic path with a high reluctance, increasing the cost of the transformer and giving one of poor characteristics. 70

One of the common points of applying current transformers of this type is at bushings where they are placed in circuit breakers, or 75 transformers, or where the leads enter buildings as the bushing provides the necessary insulation between the power conductor and ground, or the iron and secondary of the current transformer.

Where the usual bushing type of transformer is used, a single turn only is available 80 unless the conductor is threaded through the bushing a number of times, which at best requires two bushings, and in many cases is not at all applicable.

85 In high voltage lines, the amount of current is frequently relatively small, hence, where the main conductor passes through a bushing type of current transformer but once, the ampere turns provided by this primary may be too low to provide a transformer of desirable characteristics, or at best requires a transformer having a large magnetic circuit.

90 In my prior Patent No. 1,723,000, an improved type of current transformer is shown. In this type, the primary winding magnetizes 95 a central core so that even though the current is small in the power conductor, a sufficient number of ampere turns may be obtained for energizing the core of the current transformer. Where the current is small, the 100

number of turns may be increased so that the same general characteristics for the current transformer may be obtained for a high voltage conductor for any given condition 5 even though the current may be quite different in the conductor.

In many instances, the current in the power conductor may vary greatly from time to time. This is particularly true on interconnected circuits where the flow of energy is sometimes reversed. Where the amount of current in the primary covers a considerable range, it is highly desirable that the current transformer have good characteristics over 10 as wide a range as possible. While the type of current transformer shown in my prior patent, No. 1,723,000, makes it possible to provide a greatly improved current transformer over those heretofore applied to bushings for high voltage conductors, the characteristics may be further improved if the volt ampere turns are approximately the same for the magnetic circuit over a large range of current. It is possible to obtain an improved 15 characteristic for the current transformer by changing the number of turns on the primary winding when the current exceeds certain limits. It is generally advisable to change also the number of turns on the secondary side 20 of the transformer so as to maintain a constant ratio. Where this is done, the range in magnetic flux in the core may be held within much narrower limits even though the current varies over a very large range. 25 By providing the bushing primary with suitable windings, it is possible to change the number of turns by a suitable switch. Where it is desired to maintain a constant ratio, the turns in the secondary must be changed correspondingly, which can be readily taken care of by any suitable switch. In order to take 30 advantage of the improved characteristics gained thereby, it will be necessary to keep a careful watch of the magnitude of the current. The desired result, however, may be obtained by the use of a suitable automatic switch or relay. In this automatic switch or 35 relay, the current in the primary may be caused to operate a switch which will change the number of turns in the primary. By connecting the switch for the primary, with a suitable switch for the secondary, the number of turns in the secondary may be changed to correspond simultaneously with the change 40 of the number of turns in the primary, thereby maintaining a constant ratio. Any suitable means for changing both the primary and secondary simultaneously may be used. This means may be entirely outside of the 45 bushing or within the bushing as shown; the important consideration being to change the number of turns in the primary and secondary simultaneously. It, of course, is evident that the number of turns may be changed in the primary and the impedance in the second-

ary circuit changed so as to obtain the desired result without changing the number of turns in the secondary circuit.

As generally used, a current transformer will have a higher ratio on lighter currents 50 and a lower ratio on heavy currents. This tends to give inaccurate results and is objectionable for metering. The phase angle is also much poorer where the magnetizing force of the primary is low. In order to 55 avoid this difficulty, the primary may be provided with multiple windings or taps. Where the range in current is considerable, however, the characteristics of the transformer will not be good over the entire range. 60 This is corrected by providing a relay, or other means, which will automatically change the number of turns for both the primary and secondary windings, so that a good working range will be provided for the 65 current transformer over a wide range of current in the primary.

In the drawings, the numeral 10 designates the outer porcelain member of a bushing having the conductor 11 extending therethrough. Baffles 12 and 13 surround the conductor 11 and a metallic screen or flux control member 14, preferably of magnetic material, may be placed outside of the baffle 13 and supported by a ring 15 clamped between the flanges 16 and 17, secured to the upper and lower portions respectively of the outer housing 10. Surrounding the conductor 11 and separated therefrom by insulation 18 is a magnetic core 19 and a second 70 layer of insulation 20 is placed outside the core 19. Three insulated coils 21, 22 and 23 are wound, one inside the other, about the core 19; the coils being separated from one another by interposed insulation 24. The three coils are substantially identical and each consists of a flat ribbon wound helically about the core and having the ends thereof insulated from each other and carried upwardly to the top of the bushing. 75

The lower end of the coil 23 is bent about the lower edge of the insulation 24, as indicated at 25, and extends upwardly as shown by broken lines at 26. The upper end of the coil 23 is bent upwardly at 27, and the two parts 26 and 27 are insulated from each other and extend upwardly side by side to the top of the bushing. The ends of the coils 21 and 22 are carried upwardly in a like manner but the points are displaced angularly about the core from the ends of the coil 23 and from each other. The coils 21, 22 and 23 form the primary windings for the current transformer and switching mechanism is provided for placing these coils in the main circuit of the conductor 11, either singly or with two or three in series. The secondary winding of the current transformer is shown at 28 and consists of three separate coils having the ends thereof separate- 100

ly carried out through the bushing 29. Switching mechanism is provided for placing one, two or three of these coils in the secondary circuit in series with one another 5 to maintain a constant ratio between the primary and secondary coils.

The switch mechanism for the primary circuit is shown in Figs. 2 to 6 inclusive, and includes an automatically operated switch lever 30, and a hand operated switching spider 31. The arm 30 is held in the position shown in Fig. 2 by a spring 32, and is secured to a shaft 33, journalled in a pedestal 34, and provided with a magnetic armature 35. The armature 35 is controlled by a magnet 36 having a winding 37 in series with the main conductor. When current of a predetermined amount passes through the winding 37, the armature 35 will rotate the shaft 33 to shift the position of the switch arm 30 in a clockwise direction, as viewed from Fig. 2.

The switch arm 30 carries the three contact blocks 38, 39 and 40, each block being insulated from the switch arm. Each contact block is arranged to enter between contact blades carried on brackets 41, 42 and 43 respectively, the blades being insulated from each other as indicated at 44 in Fig. 6 and connected by 25 their respective contact blocks when the block is in position between the blades. The spider 31 is mounted on a shaft 45, controlled by a lever 46. The spider consists of three 30 arms carrying contact blocks 47, 48 and 49. The contact blocks 47 and 48 are electrically connected with each other but the contact block 49 is insulated from the other two blocks. The block 49 is arranged to enter between a pair of blades 50 and 51, while the blocks 47 and 48 are arranged to engage single blades 52 and 53 respectively. A pair of connecting rods 54 and 55 extend downwardly from the lever 30 inside of the bushing 10, and are connected at their lower ends to a cross arm secured to a shaft 56, journalled in a stuffing box 57 extending through the wall of the housing 10. The shaft 56, at its outer end, carries a mercury switch having three chambers 58, 59 and 60. Each of these chambers, as shown in Fig. 7, carries a pair of contacts which may be connected or separated by tilting of the mercury chamber. Contacts are connected with the secondary windings 5 of the current transformer in a manner to be more fully described. A second hand switch, shown diagrammatically at 61 in Fig. 7, is also connected in the secondary of the transformer winding. The switch 61 in its construction may be similar to the switch shown in Fig. 3. The operation of the transformer will be best understood by reference to Fig. 7. The current enters from the transmission line 62 and passes through any usual form 10 of terminal connection 98 to the relay wind-

ing 37, within the reservoir at the top of the bushing insulator.

When the switch blades 30 and 31 are in the positions shown in Figs. 2, 3 and 7, the current flows from the winding 37 through the blade 50, contact 49, blade 51 and conductor 26 to the coil 23 upon the core 19 and returns through the conductor 27 to the contact 52, and thence through the switch arm 31 to the conductor 63 to the primary winding 22, and back through the conductor 64 to the contact 65. The current then passes through the block 39 to the contact 66 and through the conductor 67 to the primary winding 21 and back through the conductor 68 to the contact 69. The current then travels through the block 38 to the contact 70 and through lead 71 to the top of the conductor 11, which passes down through the bushing. It will thus be seen that with the switches in this position, all three of the primary windings, 21, 22 and 23, are in series with the main current of the bushing, and that the winding 37 of the relay is also in series with the main conductor. If now the current increases to a predetermined amount, the relay 37 will act against the spring 32 and rotate the arm 30 so as to disengage the contact blocks 38 and 39 from their switch blades, and to bring the contact blocks 40 into position to connect the blades 72 and 73. The current will now enter from the conductor 62, passing through the winding 37, contact 51, block 49, contact 50, conductor 26, winding 23, and conductor 27 to the contact 52 and thus through the conductor 63, coil 22, and conductor 64 to the contact 65. The contact 65, however, is no longer connected to 66 so that the current passes through the jumper 74 to the contact 73, block 40, and contact 72, and thus through conductor 71 to the main conductor 11. In this position of the switch, it will be seen that only two primary coils, 22 and 23, are now in the circuit, and that the circuit leading from the coil 21 is open.

It should be noted that the contacts of the switch 30 are so arranged that the block 40 enters between the contacts 72 and 73 before the blocks 38 and 39 leave their respective contacts, so that at no time is the main circuit broken. If the current should again become weaker so that the magnet 37 will no longer hold the arm 30 against the tension of the spring 32, the arm will be returned to its original position and the coil 21 again included in the circuit. It will be noted, however, that a somewhat smaller current will hold the arm in its shifted position against the spring 32 than is required initially to shift the arm, so that there will be no point at which the switch will be in unstable equilibrium between the two positions, and consequently no chattering of the switch and vibration between its two positions. The coil 23 may be cut out of the circuit at the will 130

of the operator by shifting the hand switch 31. When this switch is rotated in a counter-clockwise direction, as shown in Fig. 7, the block 49 will be withdrawn from the contact 50 and the block 47 withdrawn from the contact 53, so that both ends of the coil 23 will be left open. At the same time, the contact 48 will engage the contact 53, so that current will flow from the relay 37 directly to the conductor 63 instead of passing first through the coil 23. An arcing gap 99 is provided between the lead 71, connected to the conductor 11, and the incoming conductor 62. It will be seen that this gap will be in parallel with the primary turns of the transformer for all combinations of these windings and will prevent subjecting these turns to excess voltage due to abnormal surges on the line or other causes.

20 When the primary windings are connected, as shown in the drawings, the secondary windings 28 will also all three be in series, as shown in Fig. 7. The secondary windings are numbered 75, 76 and 77 respectively. Starting 25 with the lower end of winding 75, as illustrated in Fig. 7, current passes through conductor 78 to contact 79, which engages block 80 on the hand switch 81. The current passes through the block 80 to contact 81' and conductor 82 to the primary winding 83 of a transformer, by means of which current is utilized. From the transformer winding 83, the current passes back through the conductor 84 to contact 85 on the magnetic switch unit 30 59 and thence to contact 86 and through conductor 87 to the winding 77, and from winding 77 through conductor 88 to contact 89, in switch unit 58. The current then passes to contact 90 and through conductor 91 to winding 76, and from winding 76 to conductor 92 and block 93 to contact 94, and thence back through conductor 95 to the winding 75. It will thus be seen that all three of the secondary windings are in series with the transformer winding 83. Now when the relay 37 shifts the switch 30, it will, at the same time, rock the mercury contact units and raise both sets of contacts 89 and 90, and 85 and 86 out of the pool of mercury, and at the same time 45 immerse the contacts 96 and 97. Current will now pass from the winding 75 through the hand switch and transformer winding 83 as before explained but instead of entering the contact 85, it will enter the contact 96 because 85 is now open. From contact 96, it will go through 97 to 91 and thence through winding 76 and back through the hand switch and contact 94 and conductor 95 to the winding 75, so that now only two windings, 75 and 76, are in the circuit. Both leads from winding 77 are open. If the hand switch 81 is shifted, the coil 75 will be cut out of the circuit, as will be readily apparent, leaving only the coil 76.

50 60 65 It will now be apparent that two coils are

provided in both the primary and secondary circuits which are automatically controlled simultaneously, so that the transformation ratio shall keep constant, although the number of turns in the primary coil is automatically adjusted to compensate for variations in the current and maintain a more nearly constant power output from the current transformer. Means is also provided for further adjusting the power output by hand. It will be apparent that the number of turns adjusted automatically may be varied by increasing the number of switch contacts controlled by relay magnets.

In some types of bushings, it is desirable to provide a capacitance tap as well as a current transformer. The design of bushing shown in the drawings is particularly adapted for obtaining the desired results. In this case, the proper ratio may be obtained by suitable taps in the secondary of the insulating transformer without changing the number of turns in the secondary winding. The insulating transformer, the primary of which is

shown at 83, Fig. 7, in addition to having leads 100 and 101 on the secondary, may have suitable taps 102 and 103 or others as required. Where these taps are used, it is not necessary to change the number of turns in the secondary. Switches like those illustrated for the secondary circuit may be used for changing the taps on the instrument or relay side of the insulating current transformer having the primary 83. Where the insulating transformer is used, the secondary winding of the current transformer is insulated from ground by baffles or any suitable means.

The secondary winding of the current transformer forms a condenser with the conductor or primary winding, thus providing an electrostatic coupling. By using the insulating transformer with primary 83, the charging current flowing to the condenser provided between the secondary winding of the current transformer and primary winding or main conductor 11 can then be made to flow through the primary 104 of a step-down transformer to provide the necessary volt ampere capacity in the secondary 105 for the operation of synchroscopes, relays, charging batteries or ratio and phase angle correction for current transformers. Where the maximum volt ampere output for the capacitance coupling is desired, the charging current between the secondary winding and the high voltage system may be further increased by electrically connecting metallized areas 110 with one coil of the winding 28 which will further increase the capacity coupling between the primary and secondary. The metallized area 110 should have a break therein so as not to form a short circuit turn for the transformer. Where the increased metallized surfaces, electrically connected to the secondary winding 28, are used as controls or

end shields adjacent to the secondary winding, the electrostatic control 14 may be omitted. If however, it is desired to retain a magnetic return 14, this may also be connected electrically to the secondary winding 28 and metalized surface 110. In this case, the insulating baffle 106 may be considerably smaller than shown. It is necessary, however, to provide insulation between the member 14 and ground by a suitable sleeve 107 or other means. It is evident that a bushing equipped with suitable current transformer may be used as a current transformer or for a current transformer and capacitance coupling, and for no other purpose. In this case, the outer or insulating sleeve may be changed to meet the conditions.

The number of turns in the several primary windings 21, 22 and 23, may be the same or different, if desired. In general, the larger the current the fewer the number of turns required. It is therefore frequently possible to provide one winding with a few turns of large current capacity and other windings having more turns to be used where the current is reduced. For instance, winding 22 may have twice the current carrying capacity of winding 21, and three times the current carrying capacity of winding 23.

Another method of providing a large current carrying capacity for the current transformer winding is to arrange the coils so that they may be used in series or parallel arrangements. A simple form of this is shown in Fig. 8 in which a primary composed of two coils, 108 and 109, are connected in series. In Fig. 9 the two coils are shown connected in parallel thereby doubling the current carrying capacity. The change from series to parallel arrangement may be effected automatically by the relay 37 and switching mechanism as shown. Other combinations of windings may be readily produced by suitable switching arrangement.

It is apparent that the useful electromagnetic flux is that which passes through both the primary and secondary coils in the same direction. By properly proportioning the core about which the primary is wound, a large percentage of the flux may be made to thread both coils of the current transformer. It is, however, not necessary that all the flux thread both coils but rather that the ratio of flux threading both coils to the total flux remain constant.

Where there is a long air path any change in the reluctance of the air path, external to the bushing, may change the ratio of flux threading the primary and secondary coils. While in general this change in flux, is of little importance, there are some cases where such changes may be undesirable. The return magnetic path provided by the shield 14 tends to insure the direction of the flux and to maintain the ratio constant, as this

magnetic shield will tend to screen the effect of adjacent metal portions such as the bushing flange, transformer, or circuit breaker cover. The ratio, however, may be made more nearly independent of outside influences by using conducting shields or turns. These shields or turns may be said to neutralize any stray field or flux which tends to take a path outside of their circumference. The member 111 may be given a plating of copper or other low resistance metal which will act as a short circuit turn. This layer will, of course, be outside of the magnetic path provided by the member 14 and core 19 and, in addition, a shield 113 made of copper or other good conducting material may be made to act as a short circuit turn eliminating the flux to a very large extent. It is evident that any electromagnetic flux which returns inside of this short circuit member 113 will have no effect upon the current in this member. Even though the member 113 is not short circuited, it will tend to prevent the flow of flux through the same. It of course is not necessary that this member be in the form of a cylinder, but it may be of any form such as a series of rings or turns of conductor or, if desired, the screening cylinder may have windows therein.

Another method of screening the effect of outside metal is to coat with copper or other good conducting metal the inner surface of the bushing wall with a layer 112 so as to form a short circuit turn. This metalizing may be carried out as shown in my previous Patent No. 1,536,749. The flanges 16 and 17, when of low resistance, produce a very effective short circuit turn. If, however, high resistance material is used, the effective screening of these members may be increased by plating or coating with copper or other coating of high conductivity. Any method which will produce the effect of a short circuit turn outside of the path of the useful flux will accomplish the desired result whether provided externally or internally of the bushing housing.

The advantages of making simultaneous changes in the number of turns in both primary and secondary windings are very considerable and easily carried out in low voltage current transformers where a high degree of accuracy is required over a wide range of current in the primary circuit. The invention is not restricted to any particular voltage.

In the form of the invention illustrated in the drawings, the switching mechanism is shown as operated from the high tension side of the transformer, but it is evident that this mechanism may be operated from the low as well as the high tension side.

I claim:

1. A current transformer in which the total current in the primary circuit is substantial-

- ly independent of the secondary circuit, said transformer having a plurality of primary turns, and automatically operated means for changing the number of turns included in the primary circuit when the current flowing therein passes a predetermined value to restrict the ampere turns in the primary to prescribed limits.
2. A current transformer in which the total current in the primary circuit depends primarily upon the apparatus electrically connected in that circuit rather than upon the load on the secondary circuit of said transformer having a number of primary turns, and means controlled by the amount of current flowing in the primary circuit of the transformer for changing the number of turns in said circuit to maintain the ampere turns in said primary within predetermined limits.
3. A current transformer in which the total current in the primary circuit depends primarily upon the apparatus electrically connected in that circuit rather than upon the load on the secondary circuit of said transformer having a plurality of primary coils, switching mechanism for connecting varying numbers of coils in the circuit of said transformer, and a relay controlled by the current flowing through said transformer for operating said switching mechanism.
4. A conductor, a current transformer in which the total current in the primary circuit depends primarily upon the apparatus electrically connected in that circuit rather than upon the load in the secondary circuit of said transformer having a plurality of primary turns arranged to be connected in series with said conductor, switching mechanism for introducing different numbers of turns in circuit with said conductor, and a relay controlled by the current flowing in said conductor for operating said switching mechanism.
5. A conductor, a current transformer in which the total current in the primary circuit depends primarily upon the apparatus electrically connected in that circuit rather than upon the load on the secondary circuit of said transformer having a number of turns arranged to be connected in series with said conductor, and switching mechanism for changing the number of turns in circuit with said conductor, said switching mechanism including a relay responsive to the current in said conductor for controlling a portion of the turns of said transformer, and a hand switch for controlling the other turns of said transformer.
6. A current transformer having a plurality of primary and secondary turns, means for changing the number of turns in the primary circuit of said transformer, and automatically operated means for maintaining a substantially constant current ratio notwithstanding changes in the number of primary turns.
7. A current transformer having a plurality of primary and secondary turns, means for changing the number of turns in the primary circuit of said transformer, and interconnected means for changing also the number of turns in the secondary circuit of said transformer and for maintaining the ratio between primary and secondary turns substantially the same for different number of turns in the primary.
8. A current transformer having a plurality of primary and secondary turns, a relay actuated by the current in said transformer for changing the number of turns in the primary, and means also operated by said relay for changing the number of turns in the secondary to maintain a constant ratio between the primary and secondary of said transformer.
9. In combination a conductor, a current transformer including a plurality of primary turns in series with said conductor, switching mechanism for changing the number of turns in the primary circuit of said transformer, and supplemental switching mechanism interconnected with the switching mechanism for the primary turns of said transformer for maintaining a substantially constant current ratio notwithstanding changes in the number of primary turns.
10. In combination a conductor, a current transformer having a plurality of primary turns arranged to be connected in series with said conductor, switching mechanism for changing the number of turns in the primary circuit of said transformer, a relay actuated by the current flowing through said conductor for operating said switching mechanism, a plurality of turns forming the secondary of said transformer, switching mechanism for changing the number of turns in the secondary circuit of said transformer, and means interconnecting the switching mechanism for said primary and secondary turns to produce simultaneous operation of said switching mechanism and maintain a constant ratio between the primary and secondary turns of said transformer.
11. A bushing insulator, having a conductor extending therethrough, a plurality of coils disposed in said bushing insulator and forming the primary circuit of a current transformer, a switch housing mounted on said bushing insulator, and switching mechanism disposed in said housing and connected with the coils in said insulator for changing the number of turns in the primary circuit of said transformer.
12. In combination a bushing insulator having a conductor extending therethrough, a current transformer having primary turns disposed in said insulator, a switch housing mounted on said insulator, switching mecha-

nism disposed in said housing and connected with the primary turns of said transformer for changing the number of turns in circuit with said conductor, a plurality of secondary turns 5 for said transformer disposed in said insulator, switching mechanism disposed outside of said insulator and connected with the secondary turns of said transformer for changing the turns in the secondary circuit 10 of said transformer, and means interconnecting the primary and secondary switching mechanism for simultaneous operation.

13. In combination, a conductor, current transformer windings excited by the current 15 in said conductor, the current in said conductor being controlled primarily by apparatus in circuit therewith rather than by the load on the secondary of said transformer, a mercury switch for changing the number of turns 20 of said transformer winding, and a relay responsive to the current in said conductor for operating said switch.

14. In combination, a conductor, current transformer windings excited by the current 25 in said conductor, separate switches for changing the number of turns respectively in the primary and secondary circuits of said transformer, means interconnecting said switches for simultaneous operation, and a 30 relay controlled by the current in said conductor for actuating said switches.

15. A current transformer having primary and secondary turns and means controlled by the current in the primary for restricting 35 the range of variation of ampere turns in said primary and for maintaining a constant transformation ratio for changes in current in the primary.

16. The combination with a bushing insulator, of a conductor extending through said insulator, a current transformer having primary turns in series with said conductor, secondary turns for said transformer, an insulating transformer in circuit with said 45 secondary turns, a ground connection through the primary of said insulating transformer to the secondary of said current transformer, and electric translating means energized by changing current flowing through said 50 grounded connection.

17. A transformer having primary and secondary windings, a core of magnetic material for directing the magnetic lines of force of said transformer, said core having an 55 air gap therein, and a shield of highly conductive, non-magnetic material disposed outside of said windings and of said core for restricting lines of force in the air space outside of said magnetic core.

18. In combination a bushing insulator, a wall of conducting material having an opening through which said insulator extends, a current transformer disposed within said insulator, and a shield for restricting the magnetic field of said transformer to minimize 65

the influence on said transformer of the magnetic characteristics of said wall, said shield comprising a closed ring of conducting material disposed outside of the outer winding of said transformer and between said winding and the periphery of the opening in said wall. 70

19. In combination a bushing insulator, a magnetic core disposed within said insulator, a primary winding surrounding said core, a secondary winding outside of said primary winding and insulated therefrom, a member of magnetic material within said insulator and outside of said secondary winding and forming a return path for the magnetic flux 80 of said transformer, and a closed ring of highly conductive non-magnetic metal disposed about said last named magnetic member and within said insulator for minimizing the effect of said transformer on magnetic material outside of said insulator. 85

20. A transformer having primary and secondary circuits, and means controlled by the current in one of said circuits for changing the number of turns in both circuits, said 90 means being constrained to change the number of turns in the two circuits simultaneously.

21. A current transformer having primary and secondary circuits, and means for automatically changing the number of turns in each circuit when the current in one of said circuits reaches a predetermined value. 95

In testimony whereof I have signed my name to this specification this 16th day of October A. D. 1929. 100

ARTHUR O. AUSTIN.
